United States Patent Office

Des. 216,381
Patented Dec. 23, 1969

216,381

CARDIAC PACING UNIT

David P. Chuboff, North Barrington, and James P. Stevens, Chicago, Ill., assignors to Zenith Radio Corporation, Chicago, Ill., a corporation of Delaware

Filed Feb. 10, 1969, Ser. No. 15,728

Term of patent 14 years

Int. Cl. D24—02; D14—02
U.S. Cl. D83—1

The figure is a left side top and front perspective view of our design for a cardiac pacing unit.

The right side (not shown) is the same as the left side shown, and the rear and bottom surfaces are plain and unornamented.

We claim:

The ornamental design for a cardiac pacing unit, substantially as shown and described.
